(57) **CLAIM**

The ornamental design for a filter cartridge, as shown and
described.

DESCRIPTION

FIG. 1 is a perspective view of a filter cartridge according to
the present design;

FIG. 2 is a first side elevational view of the filter cartridge of
FIG. 1;

FIG. 3 is a second side elevational view of the filter cartridge of
FIG. 1, taken toward an opposite side to that viewable in
FIG. 2;

FIG. 4 is third side elevational view of FIG. 2, taken toward
the right side of the view of FIG. 2;

FIG. 5 is a fourth side elevational view of the filter cartridge of
FIG. 1, taken opposite to the view of FIG. 4;

FIG. 6 is an inlet end plan view, taken toward the top of FIG.
1; and,

FIG. 7 is an outlet end plan view of the filter cartridge of
FIG. 1, the end viewable being opposite FIG. 6.

The broken lines depict portions of the filter cartridge that
form no part of the claimed design. In FIGS. 1-5, the filter
cartridge is shown with a symbolic break in its length. The
appearance of any portion of the article between the break
lines forms no part of the claimed design.
